UNITED STATES PATENT OFFICE.

PETER KELLER, OF PHILADELPHIA, PENNSYLVANIA.

GAS-REGULATOR.

SPECIFICATION forming part of Letters Patent No. 292,459, dated January 22, 1884.

Application filed June 11, 1883. (No model.)

To all whom it may concern:

Be it known that I, PETER KELLER, a citizen of the United States, residing at Philadelphia, in the county of Philadelphia and State of Pennsylvania, have invented certain new and useful Improvements in Gas-Regulators, of which the following is a specification, reference being had therein to the accompanying drawing.

10 My invention relates to an improvement in gas-regulators; and it consists in the construction and arrangement of a valve that is acted upon by a spring, and which serves to regulate the pressure of the gas, in combination with a suitable valve-seat having vents through which the moisture that may collect in the pipe above the seat will be discharged, and with a bar or plate having openings through which the gas can pass, this device 15 being adapted to be secured to the meter between it and the service-pipe, as will be more fully set forth hereinafter.

The accompanying drawing represents a vertical central section of my invention.

20 A represents a cylindrical case, which is provided at its upper end with the exterior screw-threads, A', and which is interiorly screw-threaded at its lower end, as at A'', thus enabling it to be secured to the meter at its 25 lower end and to have the service-pipe screwed to it at its upper end.

B represents a valve-seat, which has the rounded corners B', to admit of the ready escape of the gas, and the vents B'', through 30 which moisture that may collect in the case above the valve-seat may be discharged.

C represents a plate located a suitable distance above the valve D. This plate C is provided with the openings C', through which the gas can pass, and with a central opening, 40 C'', through which protrudes the stem D' of the valve D. This valve is normally pressed against the upper side of the valve-seat B by means of the coiled spring E, with which it is provided. The tension of the spring is such 45 as to only allow sufficient gas to escape from the meter to be consumed by the burners in the house to which it is to be attached, this being regulated to suit the varying sizes of the regulator that may be made.

A gas-regulator thus constructed is exceedingly simple, cheap, and serviceable, is positive and direct in its action, and is not liable to get out of order.

Having thus described my invention, I 55 claim—

The combination of the casing A, valve-seat B, having the rounded corners B' and vents B'', plates C, provided with perforations, valve D, provided with a stem, D', which extends 60 through the plate C, and spring E, all combined and arranged to operate substantially in the manner described.

In testimony whereof I affix my signature in presence of two witnesses.

PETER KELLER.
